UNITED STATES PATENT OFFICE.

GEORGE L. LAWRENCE, JR., OF MELROSE, MASSACHUSETTS, ASSIGNOR TO BOSTON RUBBER SHOE COMPANY, A CORPORATION OF MASSACHUSETTS.

RUBBER SHOE AND METHOD OF MAKING THE SAME.

1,352,008.

Specification of Letters Patent.

Patented Sept. 7, 1920.

Application filed March 26, 1920. Serial No. 369,044.

To all whom it may concern:

Be it known that I, GEORGE L. LAWRENCE, Jr., a citizen of the United States, residing at Melrose, in the county of Middlesex and State of Massachusetts, have invented certain new and useful Improvements in Rubber Shoes and Methods of Making Same, of which the following is a full, clear, and exact description.

10 This invention relates to an improvement in turned edges on lumbermen's rubber footwear, and is designed to provide a neat and efficient joint between the edges of the quarters and the edges of the tongue, as well as 15 between the edges of the quarters and the vamp and the method of producing the joints.

This is accomplished by folding over the top and front edges of the rubberized fabric quarters, which are provided on their outer faces with a comparatively thick coating of high-grade rubber, which high-grade rubber is disposed on the inner sides of the quarters to the width of the folds. This enables 25 a good, waterproofed bond to be formed between the quarters and the edges of the tongue, and between the quarters and the vamp.

The precise nature of my invention will 30 be best understood by reference to the accompanying drawings, it being obvious, however, that changes may be made in the form and details of construction of the shoe, without departing from the spirit and scope 35 of my invention as defined in the appended claims.

In the drawings,

Figure 1 is an inside face view of two quarters after they have been connected to 40 each other at the back.

Fig. 2 is a detailed sectional view on the line 2-2 of Fig. 1, and

Fig. 3 is a perspective view of one form 45 of shoe made in accordance with my invention.

In these drawings, the reference character 3-3 designates the quarters, 4 the tongue which is secured at two of its edges to the edges of the quarters 3, which is also secured 50 to the vamp 5 at the lower edge thereof.

The lower edges of the quarters of the shoe are also secured to the vamp 5 at the point 6.

55 In the manufacture of shoes in accord-

ance with my invention, the fabric from which the quarters are died is provided on its outer face with a relatively thick coating 7 of good rubber. The top and vertical edges of the quarters are then folded upon 60 themselves as indicated at 8 in Fig. 1, and the two quarters are connected to each other along their back edges as indicated at 9 to form the center of the back of the shoe. In Fig. 1 I have indicated at 8' a portion 65 of the edge before it has been folded upon itself. After the quarters are secured to each other, a tongue-forming portion is connected to each of the vertical edges of the quarters, so that the inner face of said 70 tongue-forming portions engages the surface of high-grade rubber 7 which has been folded back upon itself, as clearly indicated in Fig. 2. Eyelets 10 may then be passed through the quarters and the tongue-forming 75 portions along both the outer edges of the connected quarters, as indicated at the right hand side of Fig. 1, but if desired, buckle straps may be secured between the inturned edges of the quarters and the edges 80 of the tongue-forming portions.

The shoe is then built up in the usual manner, and the folded edges of the quarters are connected to the vamp at the points 6, and the shoes are then vulcanized.

By folding over the edges of the quarters, I am enabled to provide a good quality of rubber at the seams to form the joint between the edges of the quarters and the various members to which they are secured.

The advantages of my invention result from the provision of a vulcanized shoe having rubberized fabric quarters whose seam- 95 ing fabric edges are turned upon themselves, to bring the good facing of rubber on the exterior thereof into contact with the other members to which the quarters are to be secured along the joints, and the method of forming the joint.

Having thus described my invention, what 100 I claim and desire to protect by Letters Patent is:

1. A rubber shoe having rubberized fabric quarters vulcanized at their front edges to the edges of the tongue and the vamp, 105 said quarters having the fabric and rubber along their outer front edges folded upon themselves to bring the outer rubber faces of the quarters into contact with the edge portions of the tongue.

2. A rubber shoe having fabric quarters provided with a coating of rubber on their outer faces and vulcanized at their edges to the tongue and vamp, said quarters having the fabric and rubber along their front edges and tops folded upon themselves to bring the outer coating of rubber into contact with the edge portions of the tongue and outer portions of the vamp along the joints of said edge portions, to provide a good bonding material at said joints between said members.
3. The method of forming rubber shoes,

comprising the steps of dieing out quarters from rubberized fabric, then folding the 15 fabric edges of the quarters upon themselves to bring a portion of the rubberized outer faces of the quarters on the inner faces at the edges thereof, then building said shoe and placing said folded edges of the 20 quarters in contact with the adjacent members forming the shoe, and then vulcanizing said shoe.

Signed at Malden, Massachusetts, this 22nd day of March, 1920.

GEORGE L. LAWRENCE, JR.
